HANDHOLE CLOSURE

Clarence F. Kramer, Birmingham, and Herbert F. Cromwell, Detroit, Mich., assignors to Ford Motor Company, Dearborn, Mich., a corporation of Delaware.

Application February 12, 1943, Serial No. 475,656

3 Claims. (Cl. 244—129)

This invention relates to closures; and, more particularly, to a handhole closure having particular utility in connection with airframe construction.

The article described in this specification is a removable cover and its supporting flange designed to be incorporated into the skin construction of either the fuselage or wings of aircraft to provide access openings for inspection or adjustment of the structure therein. An advantage of the article made according to this invention is that it combines extreme lightness of weight with a faired outer surface and a readily removable yet absolutely secure locking device. Another advantage is that it offers a simplified means of installing the closure, particularly on fabric components so that it may be secured in place without initially cutting a hole in the fabric, and thus it does not permit fabric distention, which otherwise occurs when conventional closures are used. Another advantage is that locking means are provided which prevent loosening of the device or rattling in operation and which are readily incorporated in the article in the course of manufacture. Yet another advantage is that but two elements are required, each being of integral construction and being readily molded so that the saving in manufacturing cost as measured against the built-up construction heretofore used is considerable.

With these and other objects in view, the invention consists of the arrangement, construction and combination of the various parts of the improved device, as described in the specification, claimed in the claims and illustrated in the accompanying drawing in which:

Figure 1 is a plan view of the flange and closure, a portion of each element being broken away to show internal construction.

Figure 2 is a sectional view taken on the line 2—2 of Figure 1, and it shows a method of installing the closure on a fabric airframe surface.

Figure 3 is an elevation on an enlarged scale of the closure.

Figure 4 is a partial section corresponding to Figure 2, showing the method of attachment of the device to a metallic airframe component.

Referring to Figure 1, the preferred form of the invention comprises a flange 10 and a disc closure 11, both of which are preferably molded from a plastic material, although, as it will appear later, the flange may, in some instances, be formed of metal. The flange 10, as best shown in section in Figure 2, tapers outwardly and has a narrow inwardly extending ring 12 about its inner opening,

the base 13 of the ring 12 being flush with the base 14 of the flange 10 and the top 15 of the ring being spaced a different distance below the top of the flange. At intervals, in this case of 120°, the ring 12 is extended inwardly a short distance to form locking lugs 16 which may be formed with a central depression 17 on the top surface and a complementary extension 18 on the bottom surface, as best seen in Figure 3.

The closure 11 is essentially a disc 19 having finger holes 20 inset from its upper surface and a continuous depending skirt 21 spaced a short distance inwardly from the outer circumference of the disc and on the lower side thereof. At intervals, corresponding to those of the lug arrangement on the flange, the skirt 21 is extended radially outwardly adjacent its lower edge forming ridges 22. This is best shown in Figure 3 in which it will be noted that the upper surface of the ridge 22 has an initial sloping section 23 extending upwardly from the bottom surface of the skirt, a shoulder 24 and a parallel section 25 forming a retaining chamber 26 having the end wall 35. About midway of this chamber and on the lower surface of the disc 11, a detent 27 is formed, extending downwardly into the retaining chamber 26. It will be apparent that the entire closure element may be molded in one piece and no auxiliary retainers or springs are required.

In operation, the closure 11 is aligned with the flange 10 so that the lugs 16 on the flange are located between the spaced ridges 22 of the closure. The closure is then moved inwardly until the undersurface of the disc rests against the top 15 of the ring 12. The closure is then rotated in a clockwise direction, each lug 16 sliding upwardly on the sloping section 23 of each ridge 22 until it passes the shoulder 24 and then falls into the retaining chamber 26. While in this chamber, as shown in Figure 3, the detent 27 bears against corresponding depression 17 in the lug and securely locks the device in its assembled condition, the lug 16 being slightly flexed in passing between the shoulder and the detent.

The preferred method of assembling the flange 10 to a stretched continuous fabric sheet 28, such as is found in the airframe structure, is to dope the bases 13 and 14 of the ring and flange, as well as the underside of lugs 16, and place these surfaces in the desired position on the outer surface of the fabric. The dope is allowed to set, thus securing the flange in position. The fabric defined by the inner edge of the flange opening is then cut out with a sharp knife, the bottom surface of the flange and of the lugs 16, as shown

in Figure 2 at 28, being left covered with the fabric. However, by initially gluing the flange to the uncut stretched fabric, the fabric does not have a chance to distend when the hole is finally cut, as it is then supported throughout by the flange itself.

To accomplish this assembly satisfactorily, provision should be made in the spacing between the upper surface of ridges 22 and the underside of the disc 19 to allow for the additional thickness of the fabric at 28. It will be noted that this structure may be applied entirely from the outside of the plane and at any time in the course of construction after the fabric covering is in place. It may be applied with equal ease when the craft is in actual service without respect to the fact that the position may be inaccessible from the interior of the ship, which is usually the case, as otherwise it would not be necessary to provide these inspection means. To complete the assembly, a reinforcing ring 30 of fabric generally applied substantially covers the exterior portion of the flange 10 and extends over about an equal radial distance on the fabric of the structure. This is doped in place and thoroughly secures the assembly.

Provision may also be made for attaching this closure to metallic structure such as shown in Figure 4, in which case the flange 31 is made from aluminum and either riveted, as shown in 32, or welded, as indicated at 33, in position on the skin 34. This may be done quite simply as the flange is a relatively easy part to produce in metal and the closure itself may still be cast plastic, as it would be rather difficult to fabricate in any metal which would have the requisite resiliency and lightness.

Some changes may be made in the arrangement, construction and combination of the various parts of the improved device without departing from the spirit of the invention, and it is the intention to cover by the claims such changes as may reasonably be included within the scope thereof.

The invention claimed is:

1. In a handhole closure, a molded plastic ring flange having internally directed lugs, the bottom surfaces of said flange and said lugs being substantially coplanar, a molded plastic disc-shaped

closure adapted to be received centrally of said flange, depending means on said closure adjacent the circumference thereof having radially outwardly extending portions spaced from said disc forming retaining chambers closed at one end corresponding to the spacing of said lugs, the circumferential length of said chambers being substantially equivalent to the length of said lugs, said lugs being received in said retaining chambers between said disc and said extending portions, a shoulder at the other end of each said chamber on said extending portion, and an integral projecting boss formed on the lower side of said disc substantially midway of said chamber adapted to flex said lug passing between said shoulder and said boss.

2. In a handhole closure, a ring flange formed of molded plastic material having a substantially uniform width with spaced substantially flat lugs formed integrally therewith and extending radially inwardly therefrom adjacent to the bottom surface thereof, a disc closure formed of molded plastic material adapted to be centrally received in said flange and having spaced circumferentially extending retaining chambers formed integral therewith and therebeneath and having a roof and a floor opening outwardly, said chambers adapted to receive said lugs and being approximately equal in length thereto, corresponding ends of said chambers being closed, the opposite ends of said chambers having a shoulder formed adjacent the floor thereof, inclined surfaces leading to said chambers at said shoulders, a projection formed on said roof substantially midway of each of said chambers, said shoulder and said projection being so spaced that said lug in passing therebetween is flexed thereby and is locked in said chamber.

3. The structure of claim 2 which is further characterized in that said closure being adapted for installation on stretched fabric aircraft skin, said lugs and said ring have substantially coplanar bases, and said chambers are proportioned to receive said lugs with a thickness of fabric skin adhering to the lower surface thereof.
